UNITED STATES PATENT OFFICE.

BRADISH J. CARROLL, OF NEW BRIGHTON, NEW YORK.

WIRE-HOLDER.

SPECIFICATION forming part of Letters Patent No. 380,183, dated March 27, 1888.

Application filed December 28, 1887. Serial No. 259,231. (No model.)

To all whom it may concern:

Be it known that I, BRADISH J. CARROLL, of New Brighton, in the county of Richmond and State of New York, have invented a certain new and useful Improvement in Wire-Holders, of which the following is a specification.

My invention relates to a tool or device for grasping a wire for the purpose of drawing it from one place to another or for stretching it, designed principally for use in the placing of telegraph and other wires upon poles.

My objects are to increase the security of the hold on the wire and the ease with which the wire may be grasped by the tool; and my invention consists in the novel devices and combinations of devices employed by me in accomplishing these objects, as hereinafter set forth and claimed.

20 My invention is illustrated in the accompanying drawings, in which—

Figure 1 is a plan view, and Fig. 2 an end view, of a tool embodying said invention.

A is a suitable handle adapted to be grasped by the hand, and from which extend the stems B B, near the ends of which, at b b, between lugs a a, are pivoted the gripping-jaws or cams C C, which are adapted to grasp a wire, as D, between them, and which have rough-

30ened or corrugated inner surfaces for that purpose. The stems B B are each encircled by a coiled spring, E, which springs are adapted to be compressed between shoulders c on the stems and lugs d encircling the stems, which

35 are attached to or form part of the plate F, which slides on said stems against the springs and upon which the jaws C C are pivoted at e e. Upon the wire D being inserted between the jaws the plate F is moved back against the springs a greater or less distance, accord-

40 ing to the size of the wire, and then the pull on the tool, being exerted against the points b b of the gripping-jaw, brings the inner sides of said jaws against the wire, so as to grip it 45 with a powerful pressure, and the greater the strain on the wire the greater will be the gripping force of the jaws.

I so shape the gripping-jaws or cams that the same amount of surface contact will be 50 given to the wire no matter what the size of the wire is.

I am aware of the patent to Thompson, No. 83,109, dated October 13, 1868. In that patent a pair of gripping-jaws is pivoted directly

upon the handle to grasp the wire between them.

In using such an instrument the pull is directly upon the pivoted points of the jaws, and the gripping pressure is due only to this direct pull; but in my invention, since the handle is separately connected with the jaws at b b, the pull is exerted at the points other than the fulcrum-points e e, and there is an additional leverage which causes a much greater pressure upon the wire, and every additional strain gives a correspondingly multiplied addition to the hold on the wire. The strain also tends to draw the sliding plate away from the handle, and so to increase the pressure on the wire, and the springs themselves, by their pressure on the plate, force the cams together.

With my invention, also, it is much easier to grasp the wire, since by pressing the plate against the wire the same is forced back and the jaws are opened, and the tool may be then turned to bring the wire between them, whereupon the wire is at once held firmly by the tension of the springs before any strain is placed upon it.

A notch, f, may be provided in the plate F to assist in guiding the wire between the jaws.

What I claim is—

1. In a wire-holding tool, the combination 85 of a handle, a plate sliding on the handle, gripping-jaws pivoted on said plate, and connections between the handle and said gripping-jaws, substantially as set forth.

2. In a wire-holding tool, the combination 90 of the handle terminating in branching stems, the plate sliding on said stems, and the gripping-jaws pivoted on said plate and separately connected with said stems, substantially as set forth.

3. In a wire-holding tool, the combination 95 of the handle terminating in branching stems, the plate sliding on said stems, the springs pressing said plate forward, and the gripping-jaws pivoted on said plate and separately connected with said stems, substantially as set forth.

This specification signed and witnessed this 23d day of December, 1887.

BRADISH J. CARROLL.
